FIG. 4 is a left side view of the first embodiment thereof;

FIG. 5 is a right side view of the first embodiment thereof;

FIG. 6 is a top view of the first embodiment thereof;

FIG. 7 is a bottom view of the first embodiment thereof;

FIG. 8 is a perspective view of a set of keycaps showing a second embodiment of my new design;

FIG. 9 is a front view of the second embodiment thereof;

FIG. 10 is a back view of the second embodiment thereof;

FIG. 11 is a left side view of the second embodiment thereof;

FIG. 12 is a right side view of the second embodiment thereof;

FIG. 13 is a top view of the second embodiment thereof;

FIG. 14 is a bottom view of the second embodiment thereof;

FIG. 15 is a perspective view of a set of keycaps showing a third embodiment of my new design;

FIG. 16 is a front view of the third embodiment thereof;

FIG. 17 is a back view of the third embodiment thereof;

FIG. 18 is a left side view of the third embodiment thereof;

FIG. 19 is a right side view of the third embodiment thereof;

FIG. 20 is a top view of the third embodiment thereof;

FIG. 21 is a bottom view of the third embodiment thereof.

FIG. 22 is a perspective view of a set of keycaps showing a fourth embodiment of my new design;

FIG. 23 is a front view of the fourth embodiment thereof;

(Continued)

FIG. 24 is a back view of the fourth embodiment thereof; FIG. 25 is a left side view of the fourth embodiment thereof; FIG. 26 is a right side view of the fourth embodiment thereof;

FIG. 27 is a top view of the fourth embodiment thereof; and, FIG. 28 is a bottom view of the fourth embodiment thereof. The broken lines shown in the drawings depict environment on which the set of keycaps is placed and forms no part of the claimed design.
